UNITED STATES PATENT OFFICE.

JOHN RUCH AND JOHN RUCH, JR., OF PHILADELPHIA, PENNSYLVANIA,
ASSIGNORS TO THEMSELVES AND GEORGE RUCH, OF SAME PLACE.

MOTH-PROOFING HAIR.

SPECIFICATION forming part of Letters Patent No. 359,287, dated March 15, 1887.

Application filed November 9, 1885. Renewed August 16, 1886. Serial No. 211,069. (No specimens.)

To all whom it may concern:

Be it known that we, JOHN RUCH and JOHN RUCH, Jr., citizens of the United States, and residents of Philadelphia, Pennsylvania, have 5 invented an Improvement in Destroying and Preventing the Breeding of Moths in Hair, Wool, &c., of which the following is a specification.

The object of our invention is to effectually 10 destroy and prevent the breeding of moths in curled hair, such as is used for upholstering furniture; and this object we attain by boiling the mass of hair in a solution of chloride of sodium or other salt, to which is preferably 15 added a small quantity of muriatic acid.

We have found that moths and their eggs 20 or grubs which may be in the hair are destroyed by this treatment, and the hairs are provided with a permanent coating or incrustation of salt, so that the moths will not deposit their eggs upon nor will the worms or 25 grubs of the moth-fly attack them. We prefer to make a strong solution of salt—say about three quarts of salt to three gallons of water—and to this we usually add about five ounces of muriatic acid, the mass of hair in the rope being boiled in this solution for about four hours. The hair is then dried, so

as to evaporate the water and leave the salt in the crystalline form, and the hair is then 30 picked out, preparatory to use for upholstering in the usual way.

The acid has the effect of preventing the softening of the hair, which would otherwise be likely to result from long boiling of the 35 same in the salt solution. The said acid also counteracts, in a measure, the tendency which the grease upon the hair has to prevent the proper incrustation or coating of the same by the salt. 40

We claim as our invention—

The mode herein described of rendering curled hair moth-proof, said mode consisting in boiling the hair in a solution of salt and then drying it, so as to evaporate the water 45 and leave the salt in the crystalline form, all substantially as specified.

In testimony whereof we have signed our names to this specification in the presence of two subscribing witnesses.

JOHN RUCH.
JOHN RUCH, JR.
